US0D1003255S

(12) **United States Design Patent** (10) Patent No.: **US D1,003,255 S**
(45) Date of Patent: ** *Oct. 31, 2023

(54) **CONTROL DEVICE**(71) Applicant: **Lutron Technology Company LLC**,
Coopersburg, PA (US)(72) Inventors: **Benjamin F. Bard**, Zionsville, PA
(US); **Edward J. Blair**, Telford, PA
(US); **Kenneth Priester**, Austin, TX
(US)(73) Assignee: **Lutron Technology Company LLC**,
Coopersburg, PA (US)

(*) Notice: This patent is subject to a terminal disclaimer.

(**) Term: **15 Years**(21) Appl. No.: **29/853,797**(22) Filed: **Sep. 19, 2022****Related U.S. Application Data**(63) Continuation of application No. 29/773,787, filed on
